UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 18,145, dated March 6, 1888.

Application filed January 26, 1888. Serial No. 262,069. Term of patent 3½ years.

To all whom it may concern:

Be it known that I, JAMES L. FOLSOM, of Brooklyn, in the county of Kings and State of New York, have invented a new and original 5 Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face view 15 of a carpet showing my new design.

My design consists of a succession of open parts or spaces, which are ornamented alternately with cloud effects and water effects, which are skirted or inclosed with flower and

leaf forms arranged and supported for the 20 most part on arching branches or stems. Among the other flower and leaf forms are tall stems and tall narrow leaves, the former bearing flower forms resembling cat tails. In the central opening are a number of flower 25 forms resembling lily-pads. The other branches or stems are covered with long narrow leaves and short broad or triangular leaves interspersed irregularly among one another.

What I claim as new, and desire to secure 30 by Letters Patent, is—

The design for carpets, consisting of the design substantially as shown.

JAS. L. FOLSOM.
